CLAIM

We claim the ornamental design for laser light projector, as shown and described.

DESCRIPTION

FIG. 1 is a front corner perspective view of a laser light projector according to the invention. The view from the opposite front corner being a mirror image thereto.

FIG. 2 is a front elevational view of the projector.

FIG. 3 is a right side elevational view of the projector.

FIG. 4 is a rear elevational view of the projector.

FIG. 5 is a left side elevational view of the projector.

FIG. 6 is a top plan view of the projector; and,

FIG. 7 is a bottom plan view of the projector.
